UNITED STATES PATENT OFFICE.

CLARENCE B. VAN ANTWERP, OF CHICAGO, ILLINOIS.

ELECTRIC CANDLE.

1,321,495.

Specification of Letters Patent. Patented Nov. 11, 1919.

Application filed April 9, 1919. Serial No. 288,726.

To all whom it may concern:

Be it known that I, CLARENCE B. VAN ANTWERP, a citizen of the United States, residing at Chicago, in the county of Cook and State of Illinois, have invented new and useful Improvements in Electric Candles, of which the following is a specification.

This invention relates to electric candles for Christmas trees, and has for its object to provide a construction whereby the lamp socket and attached wires may be inserted into the tubular member of the candle stick from the bottom thereof and thus permit the lamp socket to be applied to the candle stick without removing the wires therefrom.

The invention consists further in the matters hereinafter described and more particularly pointed out in the appended claims.

In the drawings—

20 Figure 1 is a side elevational view of a candle stick constructed in accordance with my invention;

Fig. 2 is a horizontal sectional view taken on line 2—2 of Fig. 1;

25 Fig. 3 is a bottom plan view of the candle stick;

Fig. 4 is a vertical sectional view taken on line 4—4 of Fig. 2; and

Fig. 5 is a similar view illustrating the 30 manner in which the lamp socket is inserted into the candle stick from beneath the bottom thereof.

As shown in the drawings, a candle stick embodying the features of my invention 35 comprises a tubular member 1 open at both ends and secured to and extending above a base member 2, which in the instance illustrated is in the form of a star-shaped pan, although the same may have any other 40 ornamental shape desired. Said pan 2 is provided in its bottom wall with a hole or opening 3 having a diameter slightly greater than that of the lamp socket 4. The edge of said opening is turned upward to provide 45 a flange 5 extending upward into the lower open end of the tube 1, the latter thus opening downward through the bottom of the pan 2 and the flange 5 strengthening the connection between the tube and the pan, as 50 shown in Figs. 2 and 3. The tube 1 is provided at its lower end with ears 6 inserted downward through slots in the bottom of the pan and bent back against the pan for connecting the tube 1 therewith. For detach- 55 ably connecting the candle stick with a branch of a Christmas tree or other under-

lying support, I provide a spring clip 7, secured to the pan and extending beneath the bottom thereof. As shown in Fig. 3, said clip 7 is made U-shaped with its spaced side 60 arms 8, 8 on opposite sides of the hole 3, so that no part of the spring extends over the hole 3 to hinder the insertion of the socket 4 into the tube 1 from beneath the pan or withdrawing the socket from the tube 65 through the lower end thereof. When the clip 7 engages the branch of a tree or other part, the latter is held between the clip and the bottom of the pan 2, the side arms 8 of the clip engaging the branch at two separated points and thus serving to hold the 70 candle stick upright and prevent it from tipping.

Before the incandescent lamp bulb 9 and its socket 4 are applied to the candle stick, 75 such parts are separated, as shown in Fig. 5, and the socket 4 with its connected wires 10, 10 is inserted into the tube 1 through the opening 3 from beneath the base member 2 until the socket 4 is brought to the open upper end of the tube 1. The bulb 9 is then screwed into the socket at the upper end of the tube, and, as the bulb has a diameter greater than the tube, the bulb may rest on the upper edge of the tube for holding the parts in 80 place with the socket in the tube and the bulb 9 projecting beyond the same so that when ignited it may readily be seen and illuminate the candle stick. The wires 10 extend downward through the tube 1 and 85 out of the same through the hole 3 in the pan. As the socket 4 may be inserted into the tube 1 from beneath the bottom of the pan 2, it follows that the wires 10, 10 may be drawn into the tube with the socket, 90 thereby avoiding the necessity of being removed from the socket and permitting the latter to be readily and quickly attached to the candle stick with little difficulty.

It will of course be understood that for 100 each light in the set for the tree, a candlestick of the construction described may be used, thus not only providing a means for attaching the lights to the tree, but produce the candle effect which is so effective as a 105 means of illumination and ornament. The tube 1 and pan 2 may be painted in the same or different colors for ornamental effects and the pans may have the same or different shapes for the same reason.

I claim as my invention:

1. An electric candle for Christmas-trees

- and the like, comprising a hollow tubular member open at its ends, a lamp socket adapted to be inserted into and withdrawn from said tubular member through its lower opening without disconnecting the electrical conductors from the socket, an incandescent lamp bulb adapted to be connected to said socket and to project above the upper end of said tubular member, and a clip beneath the tubular member for attaching the candle to a support, said clip having side members separated to clear said opening at the lower end of the tubular member.
- 5 1. An electric candle comprising a base member having a hole in its bottom wall, a tubular member open at its ends and connected at its lower end to said base about the opening therethrough, a hollow tubular member open at its ends and connected at its lower end to said base about the opening 10 in the latter, a lamp socket adapted to be inserted into and withdrawn from said tubular member through said opening without disconnecting the electrical conductors from the socket, an incandescent lamp bulb adapted to be connected to said socket and to project above the upper end of said tubular member, and means adjacent said base for detachably securing the candle upon a lateral support such as a bough of the Christmas-tree.
- 15 2. An electric candle for Christmas-trees and the like, comprising a base having an opening therethrough, a hollow tubular member open at its ends and connected at its lower end to said base about the opening 20 in the latter, a lamp socket adapted to be inserted into and withdrawn from said tubular member through said opening without disconnecting the electrical conductors from the socket, an incandescent lamp bulb adapted to be connected to said socket and to project above the upper end of said tubular member, and means adjacent said base for detachably securing the candle upon a lateral support such as a bough of the Christmas-tree.
- 25 3. An electric candle comprising a hollow tubular member open at its ends, a lamp socket adapted to be inserted into and with-

drawn from said tubular member through its lower opening without disconnecting the electrical conductors from the socket, an incandescent lamp bulb adapted to be connected to said socket and to project above the upper end of said tubular member, and a clip beneath the tubular member for attaching the candle to a support, said clip having side members separated to clear said opening at the lower end of the tubular member.

4. An electric candle comprising a base member having a hole in its bottom wall, a tubular member open at its ends and connected at its lower end to said base about the hole in the latter, a lamp socket adapted to be inserted into and withdrawn from said tubular member through said hole from beneath said base member without disconnecting the wires from said socket, an incandescent lamp bulb adapted to be connected to said socket from the upper end of said tubular member and to rest thereon for holding the lamp and socket in place, and a spring clip attached to said base member and extending beneath the same and having separated side portions on opposite sides of the hole in said base member.

50 5. An electric candle comprising a base member having a hole in its bottom wall, a tubular member open at its ends and connected at its lower end to said base about the hole in the latter, a lamp socket adapted to be inserted into and withdrawn from said tubular member through said hole from beneath said base member without disconnecting the wires from said socket, an incandescent lamp bulb adapted to be connected to said socket from the upper end of said tubular member and to rest thereon for holding the lamp and socket in place, and a spring clip attached to said base member and extending beneath the same and having separated side portions on opposite sides of the hole in said base member.

55 6. An electric candle comprising a base member having a hole in its bottom wall, a tubular member open at its ends and connected at its lower end to said base about the hole in the latter, a lamp socket adapted to be inserted into and withdrawn from said tubular member through said hole from beneath said base member without disconnecting the wires from said socket, an incandescent lamp bulb adapted to be connected to said socket from the upper end of said tubular member and to rest thereon for holding the lamp and socket in place, and a spring clip attached to said base member and extending beneath the same and having separated side portions on opposite sides of the hole in said base member.

60

In testimony that I claim the foregoing as my invention, I affix my signature, this 4th day of April, A. D. 1919.

CLARENCE B. VAN ANTWERP.
